UNITED STATES PATENT OFFICE.

HERMAN C. PRIEBE, OF BLUE ISLAND, ILLINOIS.

CAR TRUCK.

Application filed August 3, 1925. Serial No. 47,883.

- My invention relates to car trucks, the invention having for one of its objects the provision of improved means for assembling the center bearing carrying members of truck bolsters with the underlying straps and a construction whereby the side frames take part in maintaining the assembly of these truck bolster members. In carrying out this object of my invention at least one end of the center bearing carrying member of a truck bolster, and preferably each end thereof, is formed with a sleeve that receives the contiguous end of the underlying strap and a key passing through the sleeve into holding engagement with the strap. The adjacent side frame has a portion which prevents the removal of the key, the side frame thus taking part in maintaining the assembly of these two truck bolster members.
- The invention has for another of its objects a cheapening in the construction of bolsters. In carrying out this object of the invention the strut that intervenes between the strap or tension member and the compression member of the bolster is formed in two upright symmetrically related parts, each part having a wing portion extending from its upper end away from the other wing. The two upright parts of the strut are bolted or riveted together. Such construction permits of the use of structural steel in the formation of a large part of the bolster, thereby lessening the cost. In the case of a truck bolster the center bearing socket and side bearings are preferably cast integrally with the compression member which overlies and is riveted or bolted to said wings, the king pin receiving bore of the socket being continued downwardly into the strut a limited distance by providing symmetrically related and matched bulges in the upper portion of the strut. The bulged portions of the strut beneath these bulges serve as a rest or support for the lower end of the king pin.
- The invention will be more fully explained in connection with the accompanying drawing in which Fig. 1 is a view in elevation, partially in section on line 1—1 of Fig. 2, illustrating the preferred embodiment of the invention, a portion of the center bearing being also illustrated; and Fig. 2 is a sectional view on line 2—2 of Fig. 1.
- The truck bolster member 1 is preferably cast in one integral structure with its center bearing socket 2, and the side bearing ele-
- ments 3. The strut member 4 underlies the member 1 and the socket 2 thereof. This strut member is formed in two equal upright portions having oppositely directed wings 4' at their upper ends. These upright portions of the strut are united by rivets while the wings are riveted to the bearing carrying or compression member 1 that serves further to tie the two parts of the strut together. The king pin receiving bore of the socket is continued into the strut by providing symmetrically related and matched bulges 4² in the upper portion of the strut, the unbulged portions of the strut below said bulges serving as a rest or support for the lower end of the king pin 4³. The bottom end of the strut is reinforced by pedestal portions 4⁴ bolted thereto and bearing upon the tension member or strap 5 which underlies the strut member and passes at its ends into the bores of sleeves 6 formed at the ends of the center bearing carrying member 1. Lugs 7 depend from the bolster member 1, these lugs being between and adjacent the sleeves and engaging the top side of the strap to hold it down. Keys 8 are passed laterally through openings that are formed in the sides of the sleeves, these keys having holding engagement with the strap through the intermediation of horizontal ridges 9 that are provided transversely upon the ends of the strap 5 to constitute hook formations. The keys are desirably in the form of flat bars arranged parallel with the ends of the strap, whereby any tendency to shearing strains between the keys and strap is resisted.
- The center bearing carrying member 1 of the truck bolster is formed with upright grooves 10 at the sides of each sleeve, the openings in the sides of the sleeves that receive the keys 8 establishing communication between the bores of the sleeves and said grooves whereby the keys may be passed transversely through the sleeves. Side frames 11 are provided, these side frames having upright portions 12 that are received in the grooves 10 whereby the center bearing carrying member 1 serves to assemble the upper portions of the side frames and whereby withdrawal of the keys is prevented after the truck bolster and side frames are assembled.
- The lower portions of the side frames carry truck bolster supporting springs 13. These springs overlie upwardly facing hooks 14 which receive the ends of a link

15 whereby the lower portions of the side frames are assembled. These hooks closely underlie the springs to enable the springs to hold the link ends in said hooks.

6 Changes may be made without departing from the invention.

Having thus described my invention, I claim:

1. A truck bolster including the center bearing carrying member thereof having a sleeve at one end and formed with upright grooves at the sides of the sleeve, said sleeve having key receiving openings formed in its sides and communicating with the bore 15 of the sleeve and said grooves; a strut member underlying the aforesaid member; a strap underlying the strut member and assembled at its ends with the center bearing carrying member, one end of the strap entering the bore of said sleeve and being formed 20 with a transverse horizontal ridge; a key received in the bore and side openings of said sleeve and in holding engagement with said ridge; and side frames assembled with the ends of said bolster and 25 one having a portion positioned to obstruct withdrawal of said key.

2. A truck bolster including the center bearing carrying member thereof having a sleeve at one end and formed with an upright groove at a side of the sleeve, said sleeve having a key receiving opening formed in a side and communicating with the bore of the sleeve and said groove; a 30 strut member underlying the aforesaid member; a strap underlying the strut member and assembled at its ends with the center bearing carrying member, one end of the strap entering the bore of said sleeve and 35 being formed with a transverse horizontal ridge; a key received in the bore and side opening of said sleeve and in holding engagement with said ridge; and side frames assembled with the ends of said bolster and 40 one having a portion received in said groove and positioned to obstruct withdrawal of said key.

3. A truck bolster including the center bearing carrying member thereof having a sleeve at one end said sleeve having key receiving openings formed in its sides and communicating with the bore of the sleeve; a strut member underlying the aforesaid member; a strap underlying the strut member and assembled at its ends with the center bearing carrying member, one end of the strap entering the bore of said sleeve and 45 being formed with a transverse horizontal ridge; a key received in the bore and side openings of said sleeve and in holding engagement with said ridge; and side frames assembled with the ends of said bolster and one having portions positioned at the ends of the key to obstruct withdrawal of said key.

4. A truck bolster including the center bearing carrying member thereof having a sleeve at one end, said sleeve having a key receiving opening formed in a side and communicating with the bore of the sleeve; a 50 strut member underlying the aforesaid member; a strap underlying the strut member and assembled at its ends with the center bearing carrying member, one end of the strap entering the bore of said sleeve and 55 being formed with a transverse horizontal ridge; a key received in the bore and side opening of said sleeve and in holding engagement with said ridge; and side frames assembled with the ends of said bolster and 60 one having a portion positioned to obstruct withdrawal of said key.

5. A truck bolster including the center bearing carrying member thereof having a sleeve at one end said sleeve having key receiving openings formed in its sides and communicating with the bore of the sleeve; a strut member underlying the aforesaid member; a strap underlying the strut member and assembled at its ends with the center bearing carrying member, one end of the strap entering the bore of said sleeve and 65 being formed with a transverse horizontal ridge; and a key received in the bore and side openings of said sleeve and in holding engagement with said ridge.

6. A truck bolster including the center bearing carrying member thereof having a sleeve at one end, said sleeve having a key receiving opening formed in a side and communicating with the bore of the sleeve; a strut member underlying the aforesaid member; a strap underlying the strut member and assembled at its ends with the center bearing carrying member, one end of the strap entering the bore of said sleeve and 70 being formed with a transverse horizontal ridge; and a key received in the bore and side opening of said sleeve and in holding engagement with said ridge.

7. A truck bolster including the center bearing carrying member thereof having a sleeve at one end and formed with upright grooves at the sides of the sleeve, said sleeve having key receiving openings formed in its sides and communicating with the bore of the sleeve and said grooves; a strut member underlying the aforesaid member; a strap underlying the strut member and assembled at its ends with the center bearing carrying member, one end of the strap entering the bore of said sleeve; a key received in the bore and side openings of said sleeve and in holding engagement with a broad side of said strap; and side frames assembled with the ends of said bolster and one having portions received in said grooves and positioned to obstruct withdrawal of said key.

8. A truck bolster including the center bearing carrying member thereof having a

- sleeve at one end and formed with an upright groove at a side of the sleeve, said sleeve having a key receiving opening formed in a side and communicating with the bore of the sleeve and said groove; a strut member underlying the aforesaid member; a strap underlying the strut member and assembled at its ends with the center bearing carrying member, one end of the strap entering the bore of said sleeve; a key received in the bore and side opening of said sleeve and in holding engagement with a broad side of said strap; and side frames assembled with the ends of said bolster and one having a portion received in said groove and positioned to obstruct withdrawal of said key. 5
9. A truck bolster including the center bearing carrying member thereof having a sleeve at one end, said sleeve having key receiving openings formed in its sides and communicating with the bore of the sleeve; a strut member underlying the aforesaid member; a strap underlying the strut member and assembled at its ends with the center bearing carrying member, one end of the strap entering the bore of said sleeve; and a key received in the bore and side openings of said sleeve and in holding engagement with a broad side of said strap. 10
10. A truck bolster including the center bearing carrying member thereof having a sleeve at one end, said sleeve having key receiving openings formed in its sides and communicating with the bore of the sleeve; a strut member underlying the aforesaid member; a strap underlying the strut member and assembled at its ends with the center bearing carrying member, one end of the strap entering the bore of said sleeve; a key received in the bore and side openings of said sleeve and in holding engagement with a broad side of said strap; and side frames assembled with the ends of said bolster and one having portions positioned at the ends of the key to obstruct withdrawal of said key. 15
11. A truck bolster including the center bearing carrying member thereof having a sleeve at one end, said sleeve having a key receiving opening formed in a side and communicating with the bore of the sleeve; a strut member underlying the aforesaid member; a strap underlying the strut member and assembled at its ends with the center bearing carrying member, one end of the strap entering the bore of said sleeve; a key received in the bore and side opening of said sleeve and in holding engagement with a broad side of said strap; and side frames assembled with the ends of said bolster and one having a portion positioned to obstruct withdrawal of said key. 20
12. A truck bolster including the center bearing carrying member thereof having a sleeve at one end, said sleeve having key receiving openings formed in its sides and communicating with the bore of the sleeve; a strut member underlying the aforesaid member; a strap underlying the strut member and assembled at its ends with the center bearing carrying member, one end of the strap entering the bore of said sleeve; and side frames assembled with the ends of said bolster and one having a portion positioned to obstruct withdrawal of said key. 25
13. A truck bolster including the center bearing carrying member thereof having a sleeve at one end, said sleeve having a key receiving opening formed in a side and communicating with the bore of the sleeve; a strut member underlying the aforesaid member; a strap underlying the strut member and assembled at its ends with the center bearing carrying member, one end of the strap entering the bore of said sleeve; and a key received in the bore and side opening of said sleeve and in holding engagement with a broad side of said strap. 30
14. A truck bolster including the center bearing carrying member thereof having a sleeve at one end; a strut member underlying the aforesaid member; a strap underlying the strut member and assembled at its ends with the center bearing carrying member, one end of the strap entering the bore of said sleeve; a key passing transversely through said sleeve and its bore and in holding engagement with a broad side of said strap; and side frames assembled with the ends of said bolster and one having a portion positioned to obstruct withdrawal of said key. 35

In witness whereof, I hereunto subscribe my name.

HERMAN C. PRIEBE.
